(57) **CLAIM**

The ornamental design for a vegetable, as shown and described.

DESCRIPTION

1.-3. Vegetable
 1.1 : Perspective
 1.2 : Top
 1.3 : Bottom
 1.4 : Side view
 1.5 : Alternative side view
 2.1 : Perspective
 2.2 : Top
 2.3 : Bottom
 2.4 : Side view
 2.5 : Alternative side view
 3.1 : Perspective
 3.2 : Top
 3.3 : Bottom
 3.4 : Side view
 3.5 : Alternative side view

1. Vegetable shaped (cut) into a cylinder lattice form; the formations are not perfectly square.; 2. Vegetable shaped (cut) into a cylinder lattice form; the formations are not perfectly square and the inside formations are straight.; 3. Vegetable shaped (cut) into a cylinder lattice form; the formations are not exactly square.
